UNITED STATES PATENT OFFICE.

EPHRAIM MANES, OF CHATTANOOGA, TENNESSEE.

HAME-TUG BUCKLE.

SPECIFICATION forming part of Letters Patent No. 641,713, dated January 23, 1900.

Application filed May 11, 1899. Serial No. 716,425. (No model.)

To all whom it may concern:

Be it known that I, EPHRAIM MANES, a citizen of the United States, residing at Chattanooga, in the county of Hamilton and State 5 of Tennessee, have invented a new and useful Hame-Tug Buckle, of which the following is a specification.

This invention relates to hame-tug buckles, and has for its object to provide a simple and 10 improved connection between the hames and the ends of the tugs or traces in which the tongue of the buckle is effectively braced against lateral movement.

To this end the invention consists in the 15 combination and arrangement of parts, as will be hereinafter more fully described, shown in the accompanying drawings, and particularly pointed out in the appended claims.

20 In the drawings, Figure 1 is a perspective view of the buckle in operative position. Fig. 2 is a longitudinal sectional view thereof. Fig. 3 is a rear plan view. Fig. 4 is a transverse sectional view taken on the line $x-x$, Fig. 3.

25 Corresponding parts are designated by like reference characters in all the figures of the drawings.

Referring to the accompanying drawings, the frame of the buckle is substantially ob- 30 long in shape, having the sides 1 and the respective end bars 2 and 3. Located about midway of the ends of the frame is a billet-loop 4, offset to one side of the frame of the buckle, and intermediate of this billet-loop 35 and the forward end 2 of the buckle there is provided another similar billet-loop 5. It will be seen by reference to Fig. 2 that the sides of the frame 6 between the billet-loops are bowed in a direction opposite to the billet- 40 loops, and a transverse pivot-bar 7 connects said bowed portions intermediate of the ends thereof. Extending forwardly from the forward end bar 2 is an integral stud 8, and projecting from the inner face of said bar and at 45 opposite sides of the finger is a pair of lugs 9, forming therebetween a substantially U-shaped forked yoke.

By reference to Figs. 2 and 3 of the drawings it will be seen that the tongue 10 is pro- 50 vided intermediate of its ends and upon the inner side thereof with a pair of wings 11,

which are adapted to be bent about the reduced portion 12 of the bar 7, whereby the tongue is pivoted to one side of the buckle and extends longitudinally thereof. The forward end of the tongue is bent into a hook 13, 55 adapted to coöperate with the stud 8, so as to close the opening of the hook. The opposite end 14 of the tongue is deflected outward and adapted to rest against the outer face of the 60 adjacent end bar 3.

In the application of the device as illustrated in Fig. 1 the hook 13 is engaged with one of the hames, and then the tug or trace 15 is engaged with the opposite end of the 65 buckle and the free end of the tug passed beneath the billet-loops 4 and 5 and across the outer face of the tongue, whereby the latter is held in its buckled or locked position, with the end of the hook 13 in engagement with 70 the end of the stud 8, and the buckle is effectively prevented from being disengaged from the hame.

As clearly shown in Fig. 3, the hook end of the tongue is normally seated between the 75 lugs of the forked yoke, whereby lateral movement of the tongue is effectively prevented. An additional guard against lateral play of the tongue is had by reason of the wings 11 embracing the reduced portion of the pivot- 80 bar engaging the opposite shoulders 16 provided thereby.

Changes in the form, proportion, size, and the minor details of construction within the scope of the appended claims may be resorted 85 to without departing from the spirit or sacrificing any of the advantages of this invention.

Having thus described the invention, what is claimed is—

1. A buckle, comprising a frame, a forked 90 yoke projecting laterally from one side of the frame at one end, and a tongue pivoted to the frame and normally seated in said yoke which prevents lateral displacement of the tongue, substantially as set forth. 95

2. A hame-tug buckle, comprising a frame, having a stud projecting longitudinally from one end of the frame, lugs located at opposite sides of the plane of the stud and projecting laterally therefrom at one side, and a tongue 100 pivoted intermediate of its ends to the frame and having one end formed into a hook

adapted to coöperate with the stud, the hook end of the tongue being normally seated between the lugs, substantially as set forth.

3. A buckle, comprising a frame having an intermediate cross-bar reduced in thickness intermediate of its ends, and a tongue provided intermediate of its ends with a pair of wings adapted to be bent about the reduced portion of the intermediate cross-bar, whereby
- 5 to the tongue is pivoted intermediate of its ends and coöperates at opposite ends with the respective ends of the frame, the wings engaging

the opposite shoulders formed by the reduced portion of the cross-bar, thereby preventing lateral movement of the tongue, substantially 15 as set forth.

In testimony that I claim the foregoing as my own I have hereto affixed my signature in the presence of two witnesses.

EPHRAIM MANES.
